United States Patent Office.

THEODORE H. MORRIS AND ERWIN SEELEY, OF WASHINGTON, DISTRICT OF COLUMBIA.

Design No. 3,738, dated November 2, 1869.

DESIGN FOR A TRADE-MARK.

The Schedule referred to in these Letters Patent and making part of the same.

To all whom it may concern:

Be it known that we, THEODORE H. MORRIS and ERWIN SEELEY, of the city of Washington, District of Columbia, have invented a Design for a Trade-Mark, to be used in connection with and on the bottle of the medicine known as Dr. Morris's Indian Ague Exterminator; and do hereby declare that the annexed is a correct drawing and description thereof.

What we claim as new, and desire to secure by Letters Patent, is—

The design of the trade-mark above represented, and substantially as it appears by the annexed drawing.

THEODORE H. MORRIS.

Witnesses: ERWIN SEELEY.
